United States Patent Office

Des. 222,086
Patented Sept. 28, 1971

222,086

BAR CABINET

Kenneth J. Guilbeaux, P.O. Box 2371,
Lafayette, La. 70501

Filed Aug. 14, 1969, Ser. No. 18,685

Term of patent 14 years

Int. Cl. D6

U.S. Cl. D33—19

FIG. 1

FIG. 2

FIG. 3FIG. 4

FIG. 1 is a top plan view of the bar cabinet embodying my new design;

FIG. 2 is an end view as seen from the right of FIG. 1;

FIG. 3 is a front view of the bar cabinet shown in FIG. 1; and

FIG. 4 is a further end view as seen from the left of FIG. 1.

I claim:

The ornamental design for a bar cabinet, substantially as shown and described.
